UNITED STATES PATENT OFFICE.

GEORGE ERWIN DE LONG, OF NEW YORK, N. Y., ASSIGNOR TO THE INDUSTRIAL MACHINE COMPANY, OF PHOENIX, NEW YORK, A CORPORATION.

MOTOR-VEHICLE.

SPECIFICATION forming part of Letters Patent No. 703,769, dated July 1, 1902.

Application filed February 25, 1901. Serial No. 48,650. (No model.)

To all whom it may concern:

Be it known that I, GEORGE ERWIN DE LONG, a citizen of the United States, and a resident of the city, county, and State of New York, have invented certain new and useful Improvements in Motor-Vehicles, of which the following is a specification.

My invention relates to motor-vehicles, and more particularly to motor-cycles.

10 My invention has for an object to do away with the auxiliary casings and attachments ordinarily removably secured to the frames of motor-cycles, and thus to greatly reduce the weight and improve the appearance thereof.

15 Other objects of my invention are to improve and simplify the construction of motor-cycles and render them more practicable and more convenient in use.

20 My invention consists in the novel parts, improvements, and combinations herein shown and described.

The accompanying drawings, which are referred to herein and form a part hereof, illustrate one embodiment of my invention and 25 serve, in connection with the description herein, to explain the principles of my invention and the best mode in which I have contemplated applying those principles.

20 Of the drawings, Figure 1 is a side elevation, partly in section, of a motor-cycle constructed in accordance with my invention. Fig. 2 is a sectional view, on an enlarged scale, illustrating a detail of the construction. Fig. 3 is a sectional elevation taken on the 35 line 3 3 of Fig. 1.

In carrying out my invention I construct a hollow or tubular frame and form the receptacles for the fuel-supply and other adjunctive devices of the motor within the hollow or tubular sections of the frame. I preferably use a gasolene-motor of the De Dion type, the explosive mixture for which is supplied by means of a carburetor of the atomizing type and the igniting devices of which consist of one 40 or more battery-cells and a sparking coil. In the drawings I have illustrated my invention as applied to a bicycle having a tubular frame of the ordinary diamond pattern.

Referring now to the drawings in detail, 1 45 represents the motor, which preferably and as shown is located directly above the main or

crank shaft 2 of the bicycle, the upright brace 3 of the frame being to this end divided at its lower portion into two or more branches or members, between which the motor 1 is secured. As shown, two branches 4 and 5 of the upright brace are provided at the rear of the motor and are made to conform to the general outline thereof. These branches 4 and 5 are secured at their lower ends to the 55 branches or members 6 and 7 of the lower rear brace of the frame, preferably at or near the point where these members are secured together by the usual transverse brace 8, which is arranged just in advance of the rear wheel 60 of the bicycle. By reason of this construction the motor and crank-bracket are brought as near as possible to the rear wheel of the bicycle, and the wheel-base of the latter is therefore not unduly extended. A third 65 branch or member 9 of the upright brace 3 is arranged in front of the motor and is preferably secured at its lower end to the lower forward brace 10 of the motor-frame. A transverse brace 11 is arranged near the top 70 or head of the motor and acts to secure the same in place and to strengthen the branches 4, 5, and 9 of the upright brace 3.

The power-shaft of the motor is provided with a small pinion 12, which meshes with a 75 larger pinion 13 on the crank-shaft 2. The opposite end of the shaft 2 is provided with a small sprocket-wheel 14, which connects with another sprocket-wheel 15 on the rear wheel of the bicycle by means of a chain 16. The 80 crank-shaft is preferably provided with a suitable clutch, so that it may be held from rotation by the rider when the bicycle is being driven by the motor, as is usual in motor-cycles. As the details of this clutch mechanism 85 do not form a feature of my present invention, they have not been shown and need not be further described.

In the construction shown the upper forward brace 17 of the frame is constructed and 90 arranged to form a receptacle for the fuel-supply of the motor. To this end the brace 17 is closed at its forward end, where it is secured to the head 18 of the frame, and the upper end of the upright brace 3 and the coupling-piece 95 or bracket 19 are so secured together and to the rear end of the brace 17 as to form a liquid-

tight connection and to constitute a part of the fuel-supply receptacle, a suitable passage 20 being provided between the braces 3 and 17. A closed socket-tube 21 is provided in the upper end of the brace 3 to receive the seat-post 22, as shown. The brace 17 is provided, preferably at its forward end, with a capped opening 23, whereby the receptacle formed in the brace may be supplied with fuel.

10 The carbureter for the motor is preferably formed in the brace 3 just above the motor. The carbureter shown comprises a supply-pipe 24, curved at its lower end, so as to discharge the liquid fuel upwardly. A valve 25 is arranged in the supply-pipe, the controlling-handle of which is arranged outside of the brace 3 within easy reach of the rider. An opening 26 is arranged above the discharge-opening of the fuel-supply pipe 24 to admit the supply of air. The opening 26 is provided with a suitable regulating-valve 26^a to control the supply of air. A perforated plate or screen 27 is arranged below the fuel-supply pipe and the air-opening, and a passage 28 is arranged below the screen 27 to convey the explosive mixture from the carbureter to the motor. A relief-cock 29 is arranged at one side of the top of the motor in position to be easily reached by the rider. The exhaust-pipe 30 of the motor is preferably arranged at the back thereof and between the members 4 and 5 of the upright brace, the lower end of the exhaust-pipe terminating in a muffler 31, which is arranged between the members 6 and 7 of the lower rear brace of the frame and just in advance of the transverse brace 8.

15 The igniting devices of the motor are preferably and as shown arranged in the lower forward brace 10 of the frame. To this end the brace 10 is extended at its lower end beneath and beyond the bracket which carries the main shaft 2 of the motor, so that the igniting devices may be inserted therein and removed therefrom. The igniting devices preferably consist of a sparking coil 35 and a plurality of battery-cells 36. As shown, an insulated contact-piece 37 is permanently fixed at the upper end of the brace 10 and the sparking coil 35, and each of the battery-cells 36 is provided at each end with a contact-piece, so that when they are put in place in the brace 10 and the lower end of the latter is closed, as by the screw-cap 38, the electric connections from the contact-piece 37 through each of the said elements of the igniting devices to the frame of the motor through the cap 38 is made complete. The contact-piece 37 is connected with an insulated wire 39, which passes through the head of the frame to a suitable switch 40, located on the frame within easy reach of the rider. The switch 40 may be connected with the usual circuit-breaker on the motor (not shown) in any suitable manner. As shown, an insulated wire 41 passes from the switch 40 down through the head of the frame and then through the lower forward brace 10 at one

side of the sparking coil and battery-cells therein to a point near the crank-bracket, where it is led to the circuit-breaker in any suitable manner. Instead of arranging the switch 40 on the head of the frame, as shown, it may obviously be located at any convenient point on the machine, as in one of the grips of the handle-bars.

75 It will be noted that aside from the motor there are no attachments secured to the outside of the frame of the bicycle. There are no casings or receptacles to mar the appearance of the machine or to be loosened by the vibrations thereof while on the road. It will be noted also that all the extra weights of the casings or carriers usually employed in motor-cycles are dispensed with, the tubular braces of the frame itself being made to take their places. 85 All parts of the apparatus are securely held in place, and the construction in general is simple and compact and not apt to get out of order.

90 My invention is not limited to the precise construction shown or to the precise construction by which it may be carried into effect, as many changes may be made therein without departing from the principles of my invention or sacrifice its chief advantages.

95 Having thus described my invention, what I claim, and desire to secure by Letters Patent, is—

1. In a motor-cycle the combination with a suitable motor, of a frame having two or more hollow sections, a receptacle for the fuel-supply of the motor formed in one of said hollow sections, and a carbureter and igniting devices for the motor located in another of said hollow sections of the frame, substantially as described.

105 2. In a motor-cycle the combination with a suitable motor and a fuel-supply for the same, of a frame having two or more hollow sections, igniting devices for the motor located in one of said hollow sections, and a carbureter for the motor located in another of said hollow sections of the frame, substantially as described.

115 3. In a motor-cycle the combination with a suitable motor and a fuel-supply for the same, of a frame having a hollow section, and igniting devices for the motor comprising one or more battery-cells and a sparking coil located in said hollow section of the frame, substantially as described.

120 4. In a motor-cycle the combination with a suitable motor and a fuel-supply for the same, of a frame having two or more hollow sections, igniting devices for the motor comprising one or more battery-cells and a sparking coil located in one of said hollow sections, and a carbureter for the motor formed in another of said hollow sections of the frame, substantially as described.

125 5. In a motor-cycle the combination with a suitable motor, of a hollow frame, a receptacle for the fuel-supply and a carbureter for the motor formed in and constituting a part

- of said hollow frame, and igniting devices for the motor comprising one or more battery-cells and a sparking coil located in said hollow frame, substantially as described.
- 5 6. In a motor-cycle the combination with a suitable motor, of a tubular frame of the diamond pattern, a receptacle for the fuel-supply formed in the upper forward brace of said frame, igniting devices for the motor located in the lower forward brace of said frame, and a carbureter for the motor located in the upright brace of said frame, substantially as described.
- 10 7. In a motor-cycle the combination with a suitable motor and a fuel-supply for the same, of a tubular frame of the diamond pattern, igniting devices for the motor comprising one or more battery-cells and a sparking coil located in the lower forward brace of the frame, and a carbureter for the motor formed in the upright brace of the frame, substantially as described.
- 15 8. In a motor-cycle the combination with a suitable motor and a fuel-supply for the same, of a tubular frame of the diamond pattern, and igniting devices for the motor comprising one or more battery-cells and a sparking coil located in the lower forward brace of the frame, substantially as described.
- 20 9. In a motor-bicycle the combination with a tubular frame of the diamond pattern, a receptacle for the fuel-supply formed in the upper forward brace of the same, a suitable motor located near the lower part of the frame, and a carbureter for the motor formed in and constituting a part of the upright brace of the frame, substantially as described.
- 25 10. In a motor-cycle the combination with a suitable motor and a fuel-supply for the same, of a tubular frame of the diamond pattern, igniting devices for the motor comprising one or more battery-cells and a sparking coil removably mounted in the lower forward brace of the frame, substantially as described.
- 30 11. In a motor-cycle the combination with a suitable motor, of a tubular frame of the diamond pattern, a receptacle for the fuel-supply formed in the upper forward brace of the frame, igniting devices for the motor comprising one or more battery-cells and a sparking coil removably mounted in the lower forward brace of the frame, and a carbureter for the motor formed in the upright brace of the frame, substantially as described.
- 35 12. In a motor-cycle the combination with a tubular frame of the diamond pattern having an upright brace divided at its lower portion, of a suitable motor located within the divided portion of the upright brace of the frame, a receptacle for the fuel-supply of the motor formed in the upper forward brace of the frame, igniting devices for the motor comprising one or more battery-cells and a sparking coil removably mounted in the lower forward brace of the frame, and a carbureter for the motor formed in the undivided portion of the upright brace of the frame, substantially as described.
- 40 13. A frame for a motor-cycle comprising two or more hollow sections, one of said sections being constructed to form a receptacle for the fuel-supply for the motor and another of said sections being constructed to form a receptacle for the igniting devices of the motor, substantially as described.
- 45 14. A frame for a motor-cycle comprising two or more hollow sections, one of said sections being constructed to form a receptacle for the fuel-supply for the motor, and other of said sections being constructed to form receptacles for the carbureter and the igniting devices of the motor, substantially as described.
- 50 15. A frame for a motor-cycle having a divided lower rear brace and an upright brace divided at its lower portion, two of the members of the divided portion of the upright brace being connected at their lower ends to the members of the lower rear brace, substantially as described.
- 55 16. A frame for a motor-cycle having a lower forward brace, a divided lower rear brace, and an upright brace divided at its lower portion, two of the members of the divided portion of the upright brace being connected at their lower ends to the members of the lower rear brace and another member of the divided portion of the upright brace being connected to the lower forward brace, substantially as described.
- 60 17. In testimony whereof I have signed my name to this specification in the presence of two subscribing witnesses.
